HARRY A. DAVIS AND ARTHUR S. JOHNSON, OF HOPEDALE, MASSACHUSETTS, ASSIGNEES TO DRAPER CORPORATION, OF HOPEDALE, MASSACHUSETTS, A CORPORATION OF MAINE.

WARP STOP MECHANISM FOR LOOMS.

Application filed August 26, 1924. Serial No. 734,234.

To all whom it may concern:

Be it known that we, HARRY A. DAVIS and ARTHUR S. JOHNSON, citizens of the United States, residing in Hopedale, in the county of Worcester and State of Massachusetts, have invented an Improvement in Warp Stop Mechanisms for Looms, of which the following description, in connection with the accompanying drawings, is a specification, like characters on the drawing representing like parts.

This invention relates to warp stop mechanisms for looms wherein a normally operated detecting member is adapted to be arrested in its movement when a warp thread breaks or becomes too slack for weaving.

Mechanical warp stop mechanisms are of two general types. One, in which the detecting member is given an oscillating or sliding movement in the general direction of the warp threads or towards and from the front of the loom, and the other, in which the detecting member is given movements transversely of the warp threads.

The present invention is adapted for use with either type, and while it is hereinafter described as associated with the second type, it is to be understood that it may be advantageously employed or associated with either.

One of the objects of the present invention is to provide a simple and effective construction of warp stop mechanism for imparting to the detecting member its detecting movements and for stopping the loom when a drop wire fails to be supported by a warp thread. In the present invention, the detecting member will be described as a toothed bar having a detecting movement transversely of the warp threads, although, as above stated, it may be utilized in association with detecting members having a different movement.

In accordance with the present disclosure of the invention, the transverse toothed bar is connected to a bar actuator which is mounted for tilting movement upon a rocker and controls a stop finger which, when the bar actuator is tilted on the rocker, effects loom stoppage.

Various novel features of the invention and new combination of parts will best be made clear from the following description

and the accompanying drawings of one good form of the invention.

55

In the drawings:

Fig. 1 is a sectional side elevation of a loom having the present invention associated therewith;

Fig. 2 is an enlarged perspective view of one end portion of the warp stop mechanism constructed in accordance with the present invention;

Fig. 3 is an enlarged side elevation, some of the parts being broken away, showing the present warp stop mechanism;

Fig. 4 is a sectional view on the line 4—4 of Fig. 3; and

Fig. 5 shows the relation of parts when one of the bar actuators is arrested in its movement with the rocker by the associated toothed bar.

In the illustrated form of the invention, four banks or rows of drop wires and associated toothed bars are shown, but it is to be understood that any number of banks or rows of drop wires may be employed.

The loom frame 1 may be of usual construction and as shown has mounted at the front thereof a shipper 2 upon which normally rests an end 3 of a knock-off lever pivoted at 4 and connected at 5 to the transmitter 6. The transmitter 6 is secured to a member 7 mounted at 8 upon a rocking link 9 pivotally supported at 10 on the loom frame. Also mounted for rocking movement about the center 8 is the dog 11 having an end portion 12 adapted to be struck by the bunter 13 mounted upon the lay as the lay moves backward, as indicated in Fig. 1. A light spring 14 overlies the dog 11 and normally holds it in inoperative position.

Below the dog 11 is the end 15 of a flexible wire which is enclosed in a flexible sheath 16, the construction being such that should the flexible wire be moved longitudinally in its sheath it will operatively position the dog 11 to be struck by the bunter 13 as the lay moves back, and when this occurs the transmitter 6 operates through the knock-off lever to stop the loom.

Rising from the loom frame 1 is a supporting rod 17 which may be adjusted vertically in the supporting bracket 18. The rod 17 is surmounted by a bracket or cap 19, Fig. 2, to which is adjustably secured a bar

or rod 20 which passes through a sleeve 21 projecting from the bracket or cap 19 and affords a support for a collar 22 which may be secured to the rod 20 in adjusted position, Figs. 2 and 3. Extending inwardly from the collar 22 is a boss 23 to which the side frame 24 of the warp stop motion is connected. The side frame 24 may be provided with the slot 25 for properly adjusting the side frames of the warp stop mechanism, and mounted in the lower part of the side frame 24 are the sockets 26, Figs. 2 and 3, for the bars 27, over which the warp threads a pass.

Extending downwardly from the hub 22 which, as previously stated, is secured to the stud 20, is the arm 28, Figs. 2, 3 and 4, for the support of a rock shaft 29. The arm 28 has a web portion 30 extending transversely of the banks of drop wires, and may be provided at the side of the web opposite the arm 28 with a similar arm 31, affording additional support for the rock shaft 29, as indicated in Figs. 3 and 4.

The web portion 30 supports the ends of the fixed bars 32 in which are mounted for reciprocating movement the toothed bars 33 operatively connected by a stud 34 with the links 35, whereby the toothed bars 33 may be given their reciprocating movement. The toothed bars 33 are reciprocated in a slot in the fixed guide bars, which may also be provided with teeth on their upper edges, the construction being such that should a drop wire 36 through which the fixed and reciprocating bars pass, fail to be supported by a warp thread, the reciprocating bar will be locked from further movement, as usual in this type of machines. In the present instance, each of the drop wires 36 is provided with a hole 37 through which the warp thread passes, in order to support the drop wires in their normal raised position.

The rock shaft 29, Figs. 2 and 3, has secured thereto the arm 38 which is itself connected at its outer end to a stud 39 joined to an operating rod 40 which may be given movement from any going part of the machine, in order to rock the rock shaft 29.

Secured to the rock shaft 29 for rocking movement therewith is a series of rockers 41 upon which are mounted the bar actuators 42, corresponding in number to the number of reciprocating toothed bars. As shown in the present instance of the invention, each bar actuator 42 is connected by a link 35 to a reciprocating toothed bar 33 to which it is pivotally connected at 43, the construction being such that as the rockers are rocked through the means described, the reciprocating toothed bars will be given their reciprocating movement.

Each rocker 41 is provided with two seats 44 and 45 which are normally engaged, as shown, by pins 46 and 47 carried by the

lower end of the bar actuators, and in order to guide the bar actuators in their tilting movement on the rocker, each of the bar actuators may be provided with a side flange 48, preferably one at each side of the associated rocker.

Between the pins 46 and 47 each bar actuator is held to the associated rocker by a spring 49, one end of which is connected at 50 to the bar actuator and the other to the rocker at 51, the construction being such that should the bar actuator be arrested in its movement with the associated rocker, it will tilt about one of the fulcra 46 or 47. The spring 49 which connects each bar actuator to its rocker preferably extends into a recess formed in the bar actuator and associated rocker, as shown, and since it acts between the fulcra of the bar actuator it normally tends to hold the bar actuator in operative position upon its rocker.

Pivotedly mounted on each rocker, as at 52, is a stop finger 53, one end of which is connected with the associated bar actuator and the other end of which is associated with means for stopping the loom should the stop finger be actuated by tilting movement of the associated bar actuator.

In the present instance of the invention, each stop finger 53 is connected with its bar actuator by a pin and slot connection, as shown. More in detail, the stop finger 53 is provided with a slot 54 which embraces a pin 55 carried by the bar actuator, the construction being such that should the bar actuator be held from movement with its associated rocker by a drop wire, the stop finger will be actuated to stop the loom.

Where a single bank of drop wires is employed, the stop finger may be directly associated with the means for stopping the loom when the stop finger is actuated by tilting movement of the bar actuator, but in most looms it is desirable to use more than one bank of drop wires and a corresponding number of bar actuators and stop fingers, and one of the features of the present invention consists of means common to all of the stop fingers to effect loom stoppage when any one of the stop fingers is actuated by its associated bar actuator.

In the present instance there is pivotally mounted on the rockers 41 at each side of the series an arm 56 which may be conveniently pivoted to the associated rocker as at 57, and extending between the outer ends of the arm 56 is a bar 58 which, as shown, underlies all of the stop fingers, whereby should any one of the stop fingers be actuated or moved relatively to its rocker by relative tilting movement of the bar actuator and rocker, it will operate through the bar 58 to stop the loom.

Within the scope of the present invention, the operative movement of the stop finger

to stop the loom may be utilized in connection with any form of loom stop mechanism, but in the present instance of the invention, a flexible wire 59 is employed within the sheath 16 hereinbefore described, and lengthwise movement of the wire in the sheath is utilized to operatively position the dog 11 to be struck by the bunter 13 when a stop finger is actuated by the bar actuator. As shown in Fig. 3, the sheathed wire 59 passes through a guide 60 formed in the end portion of an arm 61 secured to the rock shaft 29, and a spring 62 is interposed between the bar 58 and the arm 61 to normally maintain the former in its raised position under the ends of the stop fingers. Should the reciprocating bar be arrested in its movement by a drop wire, it will correspondingly arrest its associated bar actuator and cause tilting movement thereof relative to its associated rocker, as illustrated in Fig. 5, and such tilting movement of the bar actuator causes the associated stop finger 53, Fig. 5, to be moved on its associated rocker 41 to move the flexible wire 59 in its sheath and operatively position the dog 11 to stop the loom.

It will be noted from the construction described that the rocking movement of the bar actuator relative to its associated rocker will cause one end of the associated stop finger 53 to be elevated and the other depressed, regardless of the direction of the tilting movement of the bar actuator.

During normal condition of the warp threads during weaving, all of the drop wires 36 will be held in raised position to permit full reciprocating movement of the toothed bar 35, but should any warp thread break or become too slack for weaving, then the drop wire associated therewith will drop and arrest reciprocating movement of the toothed bar, and through it arrest movement of the bar actuator with its associated rocker. Such arrest of the bar actuator causes the latter to tilt on the associated rocker and through the connection with its stop finger, actuate the latter to effect loom stoppage. During normal operation of the loom with intact warp threads, the rocker or rockers and associated bar actuator, the stop finger or fingers, the arms 56 carrying the bar 58 and the arm 61 carrying the guide for the flexible wire, all move with the associated rocker, but when the associated bar actuator is arrested, its tilting movement operates the associated stop finger to stop the loom.

The construction described affords a convenient and simple construction of mechanism for stopping the loom when a warp thread breaks or becomes too slack for weaving purposes.

What is claimed is:

1. In a warp stop mechanism for looms,

the combination of a series of drop wires normally supported by the warp threads during weaving, a detector having a detecting movement and adapted to be arrested by a drop wire, a rocker, a detector actuator 70 yieldingly mounted on the rocker for tilting movement about either of two fulcra, a stop finger independently pivoted on the rocker and connected to the detector actuator as the latter is tilted by either fulcrum for 75 movement about its pivot thereby when the detector is arrested by a drop wire, and means operated by the stop finger for stopping the loom.

2. In a warp stop mechanism for looms, 80 the combination of a rocker, a bar actuator mounted for tilting movement on the rocker and normally held for such movement, a stop finger mounted on the rocker independent of the bar actuator, connections between the stop finger and bar actuator to move the stop finger upon its independent mounting relative to the rocker on tilting movement of the bar actuator on the rocker, a toothed bar connected to the bar actuator 85 for movement thereby, and means operated by the stop finger to stop the loom when movement of the toothed bar is arrested.

3. A warp stop mechanism for looms, comprising, in combination, a toothed bar 90 mounted transversely of the loom and adapted to be arrested by a drop wire, a bar actuator connected to the toothed bar, a rocker on which the bar actuator is mounted and on which it may tilt when the toothed bar 100 is arrested by a drop wire, a stop finger connected to the rocker independent of the bar actuator for movement relative thereto by the bar actuator, and means operated by the stop finger for stopping the loom when 105 the stop finger is moved relative to the rocker by the bar actuator.

4. In a warp stop mechanism for looms, drop wire detector operating means comprising a rocker, a bar actuator mounted on the rocker for tilting movement relative thereto about either of two fulcra, a stop finger mounted on the rocker and connected to the bar actuator, and means actuated by the stop finger for stopping the loom when 110 115 the stop finger is operated by the bar actuator.

5. In a warp stop mechanism for looms, toothed bar operating means comprising a rocker, a bar actuator mounted on the rocker 120 for tilting movement relative thereto about either of two fulcra, a stop finger independently mounted on the rocker and connected to the bar actuator, and a sheathed wire actuated by the stop finger for stopping 125 the loom when the stop finger is operated by the bar actuator.

6. In a warp stop mechanism for looms, the combination of a rocker, a bar actuator mounted on the rocker for relative tilting 130

- movement about centres at opposite sides of the axis of the rocker, a stop finger mounted on the rocker for movement therewith and connected to the bar actuator for movement thereby when the bar actuator is tilted on either centre, and means operated by the stop finger for stopping the loom when the stop finger is moved relative to the rocker by tilting movement of the bar actuator on the rocker.
7. In a warp stop mechanism for looms, the combination of a rocker, a bar actuator mounted on the rocker for tilting movement about either of two centres and normally restrained therefrom, a stop finger mounted on the rocker for movement relative thereto and which is given its stopping movement by bodily movement of the bar actuator as it is tilted about either centre and means for stopping the loom when the stop finger is operated by tilting movement of the bar actuator on the rocker.
8. In a warp stop mechanism for looms, the combination of a rocker, a bar actuator mounted on the rocker for relative tilting movement, a stop finger mounted on the rocker independent of the bar actuator, actuating connections between the bar actuator and independently mounted stop finger to effect stopping movement of the stop finger by lifting movement of the bar actuator, a normally inoperatively positioned dog which is placed in inoperative position to stop the loom by the stop finger when the latter is moved relative to the rocker by tilting movement of the bar actuator on the rocker.
9. In a warp stop mechanism for looms, the combination of a rocker, a bar actuator, two separated pivotal connections between the rocker and bar actuator about either of which the bar actuator may tilt, a stop finger, and connected to the bar actuator for movement thereby as the latter is lifted during its pivotal movement about either centre, a normally inoperatively positioned dog, a sheathed wire between the stop finger and dog to operatively position the dog to stop the loom when the stop finger is moved by tilting movement of the bar actuator relative to the rocker.
10. In a warp stop mechanism for looms, the combination of a series of rockers, a bar actuator mounted on each rocker for relative tilting movement, a stop finger mounted on each rocker for movement therewith and connected to a bar actuator, and means operated by any one of the stop fingers for stopping the loom when a stop finger is moved relative to the rocker by tilting movement of the connected bar actuator.
11. In a warp stop mechanism for looms, the combination of a series of rockers, a bar actuator mounted on each rocker for relative tilting movement, a stop finger mounted on each rocker for movement therewith and connected to a bar actuator, a yielding bar common to all of the stop fingers for stopping the loom when any one of the stop fingers is actuated by its associate bar actuator.
12. In a warp stop mechanism for looms, the combination of a series of rockers, a bar actuator mounted on each rocker for relative tilting movement, a stop finger mounted on each rocker for movement therewith and connected to a bar actuator, a yielding bar constructed and arranged to be operated by any one of the stop fingers, and a sheathed wire operated by the bar for stopping the loom.
13. In a warp stop mechanism for looms, the combination of a series of rockers, a bar actuator mounted on each rocker for relative tilting movement, a stop finger mounted on each rocker for movement therewith and connected to a bar actuator, a bar common to all of the stop fingers, a spring normally acting to hold the bar in position, and means operated through the bar to stop the loom when any one of the stop fingers is moved relative to its rocker by tilting movement of the associated bar actuator.
14. In a warp stop mechanism for looms, the combination of a rocker, a bar actuator mounted on the rocker and having a tilting fulcrum at each side of the centre of the rocker, a spring connecting the rocker and bar actuator between the fulcrum of the bar actuator, a stop finger carried by the rocker and operatively connected to the bar actuator, and means actuated by the stop finger for stopping the loom when the stop finger is operated by the tilting movement of the bar actuator.
15. In a warp stop mechanism for looms, toothed bar operating means comprising a rocker, a bar actuator mounted on the rocker for tilting movement relative thereto about either of two centres, a stop finger connected to the bar actuator for movement thereby into stopping position by bodily movement of the bar actuator away from the rocker as it turns about either centre, a yielding member mounted on the rocker and constructed and arranged to be moved by the stop finger and means actuated by said yielding member to stop the loom.
16. In a warp stop mechanism for looms, the combination of a series of drop wires normally supported by the warp threads during weaving, a detector having a detecting movement and adapted to be arrested by a drop wire when the latter fails to be supported by a warp thread during weaving, a rocker having a supporting surface, a detector actuator mounted for tilting movement about separate points of the supporting surface of the rocker and normally restrained from said tilting movement until the detector is arrested by a drop wire, a stop finger

- connected to the detector actuator and movable to stopping position by the lifting movement of the detector actuator as it is bodily moved relative to the rocker about either of said points when the detector and its actuator are arrested by a drop wire, and means operated by the stop finger for stopping the loom when the stop finger is operated by the detector actuator.
17. In a warp stop mechanism for looms, the combination of a drop wire detector, a rocker, a detector actuator mounted on the rocker for tilting movement about centres, one at each side of a plane passed through the axis of the rocker and longitudinal centre of the actuator, yielding means normally acting to maintain the rocker and actuator seated on both centres, a stop finger, connections between the stop finger and actuator to effect stopping movement of the former by movement of separation of the actuator and rocker as the actuator turns on either centre.
18. In a warp stop mechanism for looms, the combination of a drop wire detector, a

rocker and detector actuator having inter- 25 engaging portions constituting tilting centres at each side of a plane passed through the axis of the rocker and longitudinal centre of the detector actuator about either of which they may relatively tilt, and a stop 30 finger connected to the detector actuator to effect stopping movement of the stop finger by tilting movement of the detector actuator about either centre.

19. In a warp stop mechanism for looms, 35 the combination of a drop wire detector, a rocker, a detector actuator seated upon the rocker for movement about either of two centers, a stop finger pivotally supported and connected to the detector actuator be- 40 tween said centers to effect stopping movement of the stop finger by separating movement of the rocker and detector actuator.

In testimony whereof, we have signed our names to this specification.

HARRY A. DAVIS.
ARTHUR S. JOHNSON.
